UNITED STATES PATENT OFFICE.

ELY C. HUTCHINSON, OF OAKLAND, CALIFORNIA, ASSIGNOR TO THE PELTON WATER WHEEL CO., OF SAN FRANCISCO, CALIFORNIA, A CORPORATION OF CALIFORNIA.

LOUVER-TYPE BAFFLE PLATE.

Application filed October 21, 1924. Serial No. 744,953.

To all whom it may concern:

Be it known that I, ELY C. HUTCHINSON, a citizen of the United States, residing at Oakland, in the county of Alameda and 5 State of California, have invented certain new and useful Improvements in Louver-Type Baffle Plates, of which the following is a specification.

The present invention relates to an improved form of baffle plate for receiving and deflecting and otherwise absorbing the energy from jets or streams of water impinging upon it, to be used in connection 10 with hydraulic turbines of the impulse type.

Under normal conditions the power jet is discharged against the buckets of the water wheel runner and so long as the proper relation between the speed of the water wheel runner and the velocity of the water impinging upon its buckets exists, the water will 15 be thrown in a generally backward and downward direction as it discharges from the buckets. However, if the speed of the water wheel runner increases beyond the 20

normal, the jet or stream from the power nozzle will be carried forward more or less without particular distortion until, if the extreme were reached and the speed of the water wheel runner became equal to the 25 velocity of the jet, the jet would pass directly through the path of the water wheel runner in an almost solid form. It is necessary, therefore, to provide some means for effectively absorbing the energy of a discharging jet, or those portions of the same 30 which may carry beyond the wheel and which, if not controlled, might do serious damage to life or property. The generally accepted method for controlling and absorbing 35

the energy from the power and relief jets has been to discharge them into a vortex baffle or similar baffle but its location in the wheel pit has effectively blocked a considerable area, or avenue of discharge of the 40 power water.

The present invention has for its main object to provide a type of baffle which will effectively receive and absorb the energy from the discharging power and relief jets 45 while offering little or no obstruction to the flow of water away from the wheel pit.

With the above mentioned and other objects in view, the invention consists in the novel baffle and in its combination with the water wheel and its jet nozzles as herein-after described, illustrated in the accompanying sheet of drawings and set forth in the claims hereto annexed, it being understood that various changes in form, proportion, size and minor details of construction 55 within the scope of the claims may be resorted to without departing from the spirit or sacrificing any of the advantages of the invention.

In the accompanying drawings:

Fig. 1 is a side view, partly in section, the end frame piece of the baffle being broken away.

Fig. 2 is a vertical sectional view enlarged of Fig. 1 taken on line 2--2 and looking in 70 the direction of the arrow.

Fig. 3 is an enlarged elevation of the baffle.

Fig. 4 is an enlarged view in front elevation of the baffle.

Fig. 5 is a top plan view of the baffle.

In the drawings wherein like characters of reference designate corresponding parts, 1 indicates the water wheel runner which carries on its periphery the buckets, one 80 bucket only being here shown for convenience, and designated by 2. The water wheel runner is carried upon the overhanging shaft 3 mounted in suitable bearings within the housing 4. The water wheel runner is also provided with a cover 5, the same being held in any suitable manner. 85 6 is the wheel pit in which the lower portion of the wheel runner lies. Through one side and within the wheel pit protrude the water jet nozzles 7 and 8, one above the other. The upper nozzle 7 discharges power water upon the wheel bucket 2, thus rotating the water wheel runner. The lower nozzle 8 is for the relief jet and is so arranged that it 90 opens as the power jet is shut off, thus affording a relief to the pipe-line against the danger of water hammer. The above mentioned elements are well known in the art of hydraulic turbines of the impulse type. 95

The invention claimed to be new in this application consists primarily in the baffle 100

herein indicated as a whole by 9. This baffle is disposed at one end of the water pit 6 opposite to and in direct line with the power and relief nozzles 7 and 8, as seen in Fig. 1 of the drawings. The water ejected from these nozzles upon striking the baffle plate will be forced downward due to the construction of said baffle. The baffle consists in its best form of a column or columns of laterally curved spaced plates 10 successively overlapping and disposed at a downwardly retreating angle, said plates being carried between and supported by frame members 11, to which they are secured by rivets 11'. The plates 10 by reason of their overlapping louver-wise, and their downwardly retreating angle deflect the water impinging upon them in a downward direction. The baffle may be mounted in any suitable manner, a convenient and effective way being as follows. To the vertical frame plates 11 at their upper ends are riveted as at 12 the angle brackets 13. Riveted or otherwise attached to said brackets are the bolts 14 which pass between the spaced channel irons 15 and are secured thereto by means of the washer 16 and the locking nuts 17 and 17'. The channel irons are separated by means of the bolts 18, and are held in position by both ends being embedded in the concrete of the wheel pit.

To enable the baffle to resist the direct impact pressure of the jets, the frame plates 11 are also provided with angle brackets 19 Fig. 5. Riveted or otherwise attached to said brackets are the tie bolts 20, which pass between the spaced channel irons 21, the ends of which are embedded in the side walls of the wheel pit. The bolts 20 are secured to said channel irons 21 by means of the washers 23 and the locknuts 24 and 24'. To further secure the necessary rigidity of the baffle in this direction, there are provided the I-beams 25 between the channel irons, and the rear edges of the frame plates 11.

As heretofore intimated the generally accepted method for controlling and absorbing the energy from the power and relief nozzle jets, namely by means of a vortex baffle has by reason of its structure and its location in the wheel pit tended to block a considerable area or avenue of discharge of the power water. Present day power plant construction is tending continually to the complete and comprehensive development of entire streams in which the water discharging from one power plant empties directly into an after bay or pond, which forms the collecting basin for another power plant below. As it is desirable to conserve as much as possible of the head or fall of water from one plant to another, it becomes imperative that the design of the water wheel equipment shall be such as to reduce the loss of head to a minimum. This the present baffle accom-

plishes by effectively receiving and absorbing the energy from the discharging water jets while offering little or no obstruction to the flow of water away from the wheel jet. The curved plates are spaced and relatively disposed in such manner as to offer no open area of free discharge through which a jet impinging upon it might continue onward in its original direction; that is, jets or streams of water discharging against the baffle with some force will be received and separated into a number of parts, each of which will be diverted in a generally downward direction. On the other hand, water discharging normally from the water wheel runner into the wheel pit and moving away from the wheel pit at normal velocity will meet with a minimum resistance to its normal flow.

I claim:—

1. A baffle comprising a column of transversely curved, spaced plates successively overlapping and disposed at a downwardly retreating angle relatively to the pressure directed against them. 85

2. A baffle comprising a column of laterally curved, spaced plates successively overlapping and disposed at a downwardly retreating angle relatively to the pressure directed against them; and frame members to which the ends of said plates are secured. 90

3. A baffle comprising a column of laterally curved, spaced plates successively overlapping and disposed at a downwardly retreating angle relatively to the pressure directed against them; frame members to which the ends of said plates are secured; and means associated with said frame members for rigidly holding the baffle in place. 100

4. A baffle comprising a column of laterally curved, spaced plates successively overlapping and disposed at a downwardly retreating angle relatively to the pressure directed against them; frame members to which the ends of said plates are secured; means associated with said frame members for rigidly holding the baffle in place; compressing suspending devices applied to the top of said frame members; and compression devices applied to the backs of said frame members. 110

5. In combination with a hydraulic turbine, a base supporting the same and provided with a pit, a jet nozzle, a baffle comprising a column of spaced plates successively overlapping and disposed at a downwardly retreating angle relatively to the jet directed against them; and means for rigidly fixing said column in said turbine pit in opposition to the jet impact. 120

6. In combination with a hydraulic turbine, a base therefor and provided with a pit, a jet nozzle, a baffle comprising a column of laterally curved spaced plates successively overlapping and disposed at a 130

downwardly retreating angle relatively to the jet directed against them; and means for rigidly fixing said column in said turbine pit in opposition to the jet impact.

5 7. A baffle for absorbing the energy of a liquid jet stream, comprising a series of spaced plates successively overlapping and

disposed at a downwardly retreating angle relatively to the liquid jet stream, and means for rigidly fixing the baffle in the path of ¹⁰ the stream.

In testimony whereof I have signed my name to this specification.

ELY C. HUTCHINSON.
